(57) **CLAIM**

The ornamental design for a garbage disposal dishwasher drain cap as shown and described.

DESCRIPTION

FIG. 1 is a perspective top front right view of a garbage disposal dishwasher drain cap, showing my new design; FIG. 2 is a perspective top rear left view thereof; FIG. 3 is a front elevation view thereof, wherein the left elevation view, the right elevation view, and the rear elevation view are identical images thereof; FIG. 4 is a top plan elevation view thereof; FIG. 5 is a bottom plan view thereof; and, FIG. 6 is a cross-sectional view along the line 6-6 (see FIG. 1) thereof.
